COMPENSATING DEVICE FOR WEB
FEEDING MACHINES

William E. Sharkey, Middletown, and Ralph S. Thompson, Hamilton, Ohio, assignors to The Raymond Bag Company, Middletown, Ohio, a corporation of Ohio

Application November 19, 1930, Serial No. 496,614

14 Claims. (Cl. 271—2.6)

This invention relates to a compensating device for web feeding machines and is designed more particularly to automatically control the position of an imprint on a web of material with relation to a device which operates on that web, such as a cutter.

One object of the invention is to provide such a machine having variable speed mechanism for feeding the web to the operating device and having an improved device to cause said variable speed mechanism to correct any variation in the position of the imprint with relation to the operating device.

A further object of the invention is to provide such a machine with a device for detecting any variation in the position of the imprint which will be simple in its construction and accurate in its operation.

A further object of the invention is to provide such a machine with a variable speed feeding mechanism comprising a supplemental driving mechanism which can be operated to vary the speed at which the web is advanced by the feeding mechanism.

A further object of the invention is to provide such a machine in which the controlling mechanism may be so adjusted that it will either accelerate or retard the speed at which the web is advanced.

Other objects of the invention will appear as the mechanism is described in detail.

In the accompanying drawings Fig. 1 is a top plan view of a machine embodying my invention; Fig. 2 is a side elevation of the same; Fig. 3 is a sectional detail view of the variable speed drive for the feeding mechanism, taken on the line 3—3 of Fig. 1; Fig. 4 is a section taken on the line 4—4 of Fig. 3; Fig. 5 is a detail view of one side of the feeding and cutting mechanism; Fig. 6 is a sectional detail view of the cutters; Fig. 7 is a sectional detail view of the detector, taken on the line 7—7 of Fig. 1; Fig. 8 is an end elevation of the detector showing the driving mechanism therefor; Fig. 9 is a section taken on the line 9—9 of Fig. 1, showing the supplemental driving mechanism for the variable speed feeding device; Fig. 10 is a longitudinal sectional view taken on the line 10—10 of Fig. 1 and showing the clutch mechanism for controlling the variable speed drive; Fig. 11 is a sectional detail view showing a modified form of detector; Fig. 12 is a circuit diagram; Fig. 13 is a circuit diagram showing the connection of the modified form of detector with the controlling mechanism; and Fig. 14 is a plan view of a portion of the web.

In these drawings we have illustrated one embodiment of our invention, together with a modified form of detector, and have shown the same in connection with a machine for forming bag blanks. It will be understood, however, that this particular embodiment has been chosen for the purpose of illustration only, that the invention may take various forms and may be utilized in connection with web feeding mechanisms of various kinds.

The bag forming machine here illustrated is adapted to receive one or more webs of paper, or other material, to fold the same longitudinally into tubular form, paste the longitudinal edges of each web one to the other and deliver the folded web, or webs, to cutting mechanism which will sever the same into sections of bag length. When a multiple wall bag is to be formed a plurality of webs are passed through the machine simultaneously and are folded one about the other and delivered to the cutting mechanism in nested arrangement. That web which forms the outer wall of the bag usually has printed thereon the name of the product which is to be placed in the bag, and the name of the company furnishing such product, and/or other matter, and this imprint must occupy a certain definite position on the face of the finished bag. It is therefore necessary that the webs shall be so delivered to the cutting mechanism that the cut will be made on a predetermined line with relation to the imprint. The imprint may be placed upon the web before the latter is delivered to the machine or the mechanism for placing the imprint on the web may be a part of the machine and arranged to operate on the web in advance of the folding mechanism. The present machine is shown as adapted to form a five wall bag and five webs of paper are delivered to the machine from separate rolls, not shown. The webs pass about guide rollers 20, and the lower or outermost web 21, which carries the imprint and forms the outer wall of the bag, passes about a guide roller 22 to a guide roller 23 spaced some distance beyond the roller 22. The other webs 24 pass about guide rollers 25, spaced some distance above the roller 22, to guide rollers 26. From the rollers 23 and 26 the several webs pass about guide rollers 27 to a folding device 28a, which folds the several webs one about the other in tubular form and the nested tubes are delivered to the cutting mechanism, which is here shown as comprising an upper roller 29 and a lower roller 28, the upper roller 29 having a blade 30 arranged to sever the nested tubes across their entire width. 55

The arrangement of the guide roller 22 with relation to the guide rollers 25 results in spacing the outer web 21 some distance from the other webs, thus providing space within which the detector may be applied to the outer web. Inasmuch as the invention is applicable to a machine handling a single web as well as to a machine handling a plurality of webs and the additional webs are in no way concerned with the invention, 5 the term "web" will be herein used as referring either to a single web of material or to that one of several webs of material which carries the imprint. The term "imprint" as here employed is intended to include any marking or other characteristic which may be placed upon or imparted to the web, whether placed thereon by printing or otherwise.

The mechanism may be driven from any suitable source or sources of power but, in the present instance, the machine as a whole is driven by an electric motor 31 which is connected by a chain 32 with a sprocket wheel 33 on the main drive shaft 34, extending transversely to a main frame. A gear 35 on the drive shaft meshes with a gear 36 on the shaft of the lower cutter roller which gear also meshes with a gear 37 on the upper cutter roller. At that end opposite the gear 36 the shaft of the lower cutter roller has secured thereto a gear 38 which is connected through an idle gear 39 with a gear 40 on the shaft 41 of the lower feed roller 42. An upper feed roller 43, here shown as comprising two narrow rollers or disks, is carried by a shaft 44 which is driven from the shaft 41 of the lower feed roller in a manner to be hereinafter described. These feed rollers serve to draw the web, or webs, of material from the supply rollers through the folding mechanism and to deliver the same to the cutting rollers. The severed bag sections are withdrawn and delivered from the machine by feeding out rollers 45 which are driven by a chain 46 from the lower cutter roller shaft. The imprint on the web must occupy a certain definite position on the finished bag and it is therefore essential that the webs should be so delivered to the cutting mechanism that the line of severance of each bag section will be at a definite distance from the imprint. The arrangement and timing of the feeding rollers are such that normally a section of the web, equal in length to the bag, will be delivered to the cutters upon each operation thereof, thereby maintaining the imprints in proper position with relation to the cutter. In the operation of the machine the position of the imprint with relation to the cutters will sometimes vary due either to the slippage of the feed rollers on the web, the inaccurate spacing of the imprints on the web by the printing mechanism, or for other reasons and any such variation must be promptly corrected. For the purpose of correcting such variations we have provided variable speed mechanism for driving the feed rollers 42 and 43 and automatically controlled means for causing this variable speed mechanism to accelerate or retard the speed at which the web is advanced so as to correct the position of the imprint with relation to the cutters.

In the present arrangement of the machine the variable speed mechanism is mounted in a gear box 47 supported on the main frame at one side thereof and the main drive shaft 41 extends into this gear box. The lower feed roller 42 is carried by a sleeve 48 which is rotatably mounted on the shaft 41 and extends into the gear box 70 where it is provided with a gear 49. A gear 50

secured to the sleeve 48, preferably between the gear box and the main frame and meshes with a gear 51 secured to the shaft 44 of the upper feed roller, so that the two feed rollers are caused to rotate in unison in opposite directions. Mounted 5 within the gear box for rotation about the axis of the main feed shaft 41 is a supporting member or frame 52 which, as here shown, has an elongated hub 53 which is journaled in a bearing in the outer wall of the gear box and in which the 10 adjacent end of the main feed shaft 41 is rotatably supported. Rigidly secured to the main feed shaft 41 is a gear 54 having an elongated hub 55 on which is mounted a sleeve 56 having rigidly secured thereto, at its respective ends, 15 gears 57 and 58. The gears 57 and 58 are of the same diameter as the gear 54 and have a slightly smaller number of teeth, in the present instance the gear 54 has thirty-six teeth and the gears 57 and 58 have thirty-five teeth each. The gear 20 49 on the sleeve 48 is of the same diameter as and has the same number of teeth as the gear 54. The gears 54 and 57 mesh, one side of the shaft, with a planetary gear 59 which is of sufficient width to mesh simultaneously with both gears. 25 The gears 54 and 57 being rotatable with relation to each other will assume a position in which the teeth thereof will be in line at that point where they mesh with the gear 59 but will be slightly out of line on the opposite side of the shaft. The 30 gear 59 is carried by a short shaft 60 which is supported at one end in the rotatable supporting member or frame 52 and at the other end in an annular frame or collar 61 which is rotatably mounted within the gear box. The gears 54 and 35 57 mesh, on that side of the shaft opposite the gear 59, respectively, with gears 62 and 63, which are mounted on a stud 64 carried by the supporting member and the collar. These two gears 62 and 63 have the same number of teeth, in the 40 present instance twenty-seven, and are rigidly connected one to the other in such positions that the teeth will be slightly out of line so that the gear 62 will mesh with the gear 54 and the gear 63 will mesh with the gear 51, the teeth of the 45 gears 54 and 57 being slightly out of line at the point at which they engage the gears 62 and 63. The gear 58, which is rigidly connected with the gear 51, meshes with a gear 65 having rigidly secured thereto a gear 66 which meshes with a gear 50 49 on the sleeve 48. The gears 65 and 66 are carried by a stud 67 supported at one end in the end wall of the gear box and at the other end on a stationary frame or collar 68. The gears 65 and 66 have the same number of teeth as the 55 gears 62 and 63 and the teeth of the two gears are slightly out of line so that they will mesh simultaneously with the gears 58 and 49. The gears 58 and 49 also mesh with a wide gear 69 arranged on the opposite side of the shaft and 60 carried by a stud 70 mounted in the end wall of the gear box and in the fixed collar 68. Rigidly secured to the supporting member 52 is a worm gear 71 which meshes with a worm 72 on a shaft 73 which extends lengthwise of the machine beyond the rear side of the gear box 47. The shaft 73 and worm 72 are normally stationary but may be rotated in one direction or the other to impart a like movement to the supporting member 52. When the worm 72 is stationary the supporting 70 member will be held against movement and the rotation of the shaft 41 and gear 54 will cause the gears 62 and 63 to rotate and this movement will be imparted through the gears 57 and 58 and the gears 65 and 66 to the gear 49 on the sleeve 75

48, thus causing that sleeve and the feed rollers to rotate at the same speed at which the shaft 41 is rotated. If the worm 72 is rotated in a direction to impart forward rotation to the supporting member 52 the gears 62 and 63 will not only be rotated by the gear 54 on the main feed shaft but will be rotated with relation thereto and will thus impart movement to the gears 57 and 58 in addition to the movement imparted thereto by the gear 54 and will thereby cause those gears to move at a speed slightly greater than the speed at which the shaft 41 rotates. In the present arrangement the difference in the rotations of the gears 57 and 54 is equal to one tooth for each 15 complete rotation of the supporting member. The accelerated movement of the gears 57 and 58 will be transmitted through the gears 65 and 66 to the gear 49 on the sleeve 48, thus causing the feed rollers to be actuated at a speed slightly greater than the speed at which the shaft 41 is rotated. Consequently if the imprint on the web has lagged slightly behind its normal position the accelerated speed of the feed rollers will return the same to its normal position. Should the 20 supporting frame 52 be rotated in a reverse direction the gears 57 and 58 will be retarded and a slower movement will be imparted to the web, thus retracting the imprint with relation to the cutting mechanism.

25 The means for imparting rotation to the shaft 73 which controls the speed at which the feed rollers are operated and for determining the direction at which that shaft is rotated may take various forms. In the present instance, the shaft 35 73 is driven from the main drive shaft 34 through suitable clutch connections, part of which are automatically controlled. Extending lengthwise of the main frame is a shaft 74 connected at its forward end with the main drive shaft 34 by 30 beveled gears 75. Rotatably mounted on the main frame adjacent to the shaft 74 is a short shaft 76 and rotatably mounted on this shaft is a clutch member 77 having rigidly secured thereto a pinion 78 which is connected, through an 35 idle gear 79, with a gear 80 on the shaft 74, thus causing the clutch member 77 to be driven from the shaft 74 and to rotate in the same direction as that shaft rotates. Cooperating with the clutch member 77 is a clutch member 81 which is splined 40 on or otherwise so connected with the shaft 76 that it will rotate therewith and have axial movement with relation thereto so that it may be moved into and out of operative engagement with the clutch member 77. A second clutch member 45 82 is also splined on the shaft 76 and adapted to cooperate with a clutch member 83 rotatably mounted on the shaft and having rigidly secured thereto a pinion 84 which meshes with a gear 85 on the shaft 74, thus causing the clutch member 83 to be rotated from the shaft 74 in a direction opposite to the direction in which said shaft rotates. The two clutch members 81 and 82 have connected therewith a grooved collar 86 adapted to be engaged by a shifting yoke 87 by 50 means of which axial movement may be imparted to the clutch members. The clutch members are so connected one to the other that when one is moved into operative engagement with its co-operating clutch member the other will be moved to an inoperative position. The shifting yoke 87 is carried by a shaft 88 extending transversely to the machine and having at one end an operating handle 89. Rotatably mounted on the shaft 76 near the rear end thereof is a clutch member 90 which, in the present instance, has an elongated hub 91 journaled in a bearing 92 and in which the shaft 76 is rotatably supported. Rigidly secured to the hub 91 of the clutch member 90 is a sprocket wheel 93 which is connected by a chain 94 with a sprocket wheel 95 on the shaft 5 10 73. Cooperating with the clutch 90 is a clutch member 96 splined or otherwise secured to the shaft 76 for axial movement with relation thereto but for rotation therewith. It will be apparent, therefore, that when the clutch member 96 is seated in its cooperating clutch member, and either of the clutch members 81 or 82 are seated, the shaft 73 will be driven from the shaft 74 in a direction determined by the clutch members 81 and 82. The clutch member 96, which serves 15 to start and stop the shaft 73 of the variable speed mechanism, is power operated in such a manner that it may be automatically controlled and preferably is actuated by electrically operated devices. In the present instance, a coupling 20 member 97 is operatively connected with the clutch member 96 and is connected with one arm of a toggle 98, the other arm of which is connected with a fixed support 99. In the present device, a spring 100 is interposed between the last mentioned arm of the toggle and the fixed support 99 and tends to hold the toggle in the position to which it has been moved. The electrically operated devices are shown as comprising two solenoids, 101 and 102, the cores of which are connected with a yoke 103 which embraces a stud 104 connected with the toggle at the point of pivotal connection of the two arms thereof. It will be apparent, therefore, that when the solenoid 101 is energized the parts will assume the 30 position shown in Fig. 10 and the clutch member 96 will be moved to an inoperative position. When the solenoid 102 is energized the toggle will be straightened and the clutch member 96 seated in the clutch member 90, thus establishing the 35 operative connection between the shaft 76 and the shaft 73. The movement of the toggle to seat the clutch member 96 carries the same to or slightly beyond the aligned position of the two arms thereof and the action of the spring 100 will hold the arms in that position after the solenoid has been deenergized and until transverse pressure is applied thereto.

40 The circuits for the electrically operated device which controls the action of the speed varying mechanism are automatically controlled in accordance with the position of the imprint on the web with relation to the cutting mechanism. In the present instance, the web 21 is provided with a series of apertures 105, one for each imprint. These apertures are preferably formed in the web simultaneously with the placing of the imprints thereon so that each aperture will occupy a certain definite position with relation to the corresponding imprint irrespective of the 50 position of the imprint on the web. Cooperating with the apertures in the web is a detector which preferably comprises a rotatable part driven in timed relation with the cutting mechanism and so positioned that when the imprint on the web 55 is in proper relation to the cutting mechanism the part will not register with the aperture in the web but, when the web assumes an abnormal position with relation to the cutting mechanism, the rotatable part will register with the aperture 60 65 70 in the web and will operate therethrough to close the circuit through the electrically operated device. The detector may take various forms and, in the preferred embodiment of the invention, we have illustrated a detector which is controlled 75

by the passage of light through the web. The detecting device as a whole comprises a casing 106 having the top wall arranged beneath the web, in the present instance between the guide 5 rollers 22 and 23, and forming a support therefor. The casing is divided by a partition 107 into two compartments 108 and 109 and each compartment has in its top wall an opening 110. Located in each compartment, near the bottom thereof, is a photo-electric cell, or a selenium 10 cell, 111. Arranged between the photo-electric cell and the opening 110 in each compartment is a lens 112 which is adapted to focus the light entering the compartment through the opening 110 onto the photoelectric cell. Mounted above the casing 106, and above the web, are two rotatable drums 113 and 114, each having in its peripheral wall an opening 115 but being preferably otherwise closed against admission of light. 15 These drums are rotated in the same direction in accurately timed relation to the movement with the cutting mechanism. In the present arrangement, the shaft 74 has secured thereto a worm 116 which meshes with a worm wheel 116a 20 to which is secured a sprocket wheel 117. This sprocket wheel is connected by a chain 118 with sprocket wheels 119 and 120 on the drums 113 and 115 so that these drums will be driven in the same direction and at a predetermined speed 25 with relation to the shaft 74 and the cutting mechanism. If desired, one or both drums may be adjustable, as shown at 121, so that the relative positions of the openings in the two drums may be adjusted. The drums are arranged close 30 to the upper surface of the web but are preferably out of contact therewith. Each drum is provided, on that side thereof opposite the opening 115 therein, with an electric lamp 122 and between this lamp and the opening 115 is a lens 40 123 which serves to focus the light from the lamp into the opening 115. The two drums are normally so arranged that when the imprint on the web is in its proper position with relation to the cutting mechanism the openings 115 will 45 not register with the aperture 105 in the web but when the web lags, or if for any other reason the imprint is behind the position it should occupy, the opening 115 in the drum 114 will register simultaneously with the aperture 105 in the web and with the opening 110 in the compartment 109 of the housing, thereby causing the ray of light to pass through the opening 110 and to be focused onto the photoelectric cell. This 50 will operate through a series of mechanisms to be hereinafter described to initiate the operation of the speed varying mechanism and cause the speed at which the feeding mechanism is driven to be accelerated, thus restoring the imprint to its proper position with relation to the cutting mechanism. When the imprint has been 55 returned to, or slightly beyond, its proper position, the opening 115 in the drum 113 will register with the aperture in the web, thus causing the ray of light to be focussed on the photo-electric cell in the compartment 108 of the housing and this will cause the operation of the speed varying mechanism to be interrupted and there- 60 by restore the normal speed of operation for the feeding mechanism.

70 In the present embodiment of the invention we have, for the purpose of illustration, shown portions of the web cut away to provide the apertures 105 which control the passage of the light through the web to the photoelectric cell but it 75 will be obvious that the passage of the light

through the web may be controlled in various ways and the term "aperture" as herein employed is intended to include any means operating in a similar manner to control the passage of the light.

The construction and operation of the photo-electric cell form no part of the present invention and inasmuch as these are well known they will be described only to the extent necessary to make clear the operation of the present device. As 10 shown in the circuit diagram of Fig. 12, a conductor 124, leading from a source of supply for direct current, is connected by a conductor 125 through the coil 126 of a relay and a conductor 127 with one side of the photo-electric cell 111 15 in the compartment 109 and the other side of this cell is connected by conductors 128 and 129 with a conductor 130 which leads back to the source of current. A conductor 131 connects the line 124 through the coil 132 of a relay and a conductor 20 133 with the photo-electric cell 111 in the compartment 108 and this cell is connected by conductors 134 and 135 with the line 130. The conductors 127 and 128 are connected, respectively, with the plate 136 and the grid 137 of an amplifying tube and the filament 138 of this amplifying tube is connected by conductors 139, 140 and 141, with one end of the secondary of a transformer, the other side of the filament being connected by 25 a conductor 142 with the secondary, preferably at a point between the ends thereof so that a portion only of the secondary voltage is delivered to the filament. The same connections exist in the compartment 108 where the grid 137 is connected with the conductor 134 and the plate 136 is connected with the conductor 133. The filament 138 30 is connected by a conductor 143 with the conductor 139 and by a conductor 144 with the conductor 142. The primary coil of the transformer, which is indicated as a whole by the reference 40 numeral 145, is connected by conductors 146 with a source of supply of alternating current. The relay 126 is connected by a conductor 147 with a conductor 141 leading to the secondary of the transformer and by a conductor 148 with a reversing switch which is indicated as a whole by the reference numeral 149. With the switch in the position shown in Fig. 12 the conductor 148 45 is connected through the arm 150 of the switch and the cross connection 151 with a conductor 50 152 which is connected with the coil 153 of a relay 154, the opposite end of this coil being connected with a conductor 155 which leads back to the secondary of the transformer. This relay 55 controls two circuits, one of which serves to energize the solenoid 102 which closes the clutch 96 to initiate the acceleration of the feeding mechanism, and the other of which maintains the relay itself energized until the solenoid has completed its operation, irrespective of the relay 60 126. The solenoid circuit comprises a conductor 156 leading from the source of current supply to the relay, a conductor 157 leading from the relay to the solenoid 102 and conductors 158 and 159 leading from the solenoid back to the source of 65 current supply. The coil 153 of the relay is connected by a conductor 160 through the relay itself with a second conductor 161 which leads through a switch 162 to a conductor 163 leading back to the secondary of the transformer, so that when 70 the relay is operated the circuit through the coil will be completed from the secondary through the conductor 155, coil 153, conductors 160 and 161, switch 162 and conductor 163 back to the secondary. Therefore, the opening of the relay 75

126, which takes place after a very brief interval, will not interrupt the solenoid circuit. The switch 162 is so arranged that it will be engaged and opened by a plunger 164, or other part, connected with the solenoid core, this opening of the switch taking place after the clutch has been operated and, as has been heretofore explained, the clutch is mechanically held in its closed position after the solenoid is deenergized. With the 10 clutch set as above described the movement of the web is accelerated until the imprint is brought back to or slightly beyond its correct position, at which time the opening 115 in the drum 113 will register with the aperture in the web and with the opening 110 in the compartment 108 of the housing, thus energizing the photo-electric cell in that compartment and thereby causing the relay 132 to be closed in the same manner that the relay 126 was closed. The relay 132 is connected 20 on one side by a conductor 165 with the conductor 140 leading from the secondary of the transformer. A conductor 166 leads from the other side of the relay to the reversing switch 149 and through one arm 167 of that switch and a cross connection 168 to a conductor 169 which leads to the coil 170 of a relay 171, thus energizing that relay and closing the circuit through the solenoid 101 which functions to move the clutch member 96 to its inoperative position and thus interrupt 30 the acceleration of the web. The solenoid circuit comprises a conductor 172 leading from the conductor 156 to the relay, a conductor 173 leading from the relay to the solenoid and a conductor 174 leading from the solenoid to the line 159. 35 A conductor 175 leading from the relay coil is connected through the relay itself, a conductor 176, switch 177, a conductor 178 with the conductor 163 leading back to the secondary of the transformer, thus when the relay 171 has been 40 operated it will be retained in its closed position after the relay 132 has opened and until the switch 177 is opened by the solenoid, which has a part, such as a plunger 179, arranged to engage and open that switch.

45 The present machine is adapted to correct displacements of the imprint in one direction only. As above described, the mechanism operates to accelerate the speed of the web to advance the imprint when it has lagged behind its normal position. By reversing the operation the mechanism may be caused to retard the feeding of the web when the imprint has moved ahead of its normal position. In the present arrangement, the mechanism does not function automatically to 50 both accelerate and retard the movement of the web but a manual operation is required to change the operation from acceleration to retardation. To reverse the mechanism from the accelerating position to the retarding position the manually operated device 89 is actuated to reverse the position of the clutch members 81 and 82 and thus so connect the shaft 73 of the speed varying mechanism that it will be driven in the opposite direction. The reversing switch 149 is actuated to 55 break the connection of one end of the arm 15 at the cross connection 151 and to establish a connection between the other end of the arm 150 and the conductor 169, thus connecting the photo-electric cell in the compartment 109 with the relay 171. The reversing of the switch 149 also breaks the connection between one end of the switch arm 167 and the cross connection 168 and connects the other end of that arm with the conductor 152 leading to the relay 154, thereby connecting the photo-electric cell in the compartment

108 with the relay 154. It will thus be apparent that the rotary part or drum which had formerly served to interrupt the operation of the speed varying mechanism now becomes the starting device which initiates the operation of the speed varying mechanism and that the drum 114 which formerly served to initiate this operation now serves to stop the same. Consequently when the imprint moves to a position in advance of its normal position the opening 115 in the drum 113 will register with the aperture in the web, thus causing the photo-electric mechanism in the compartment 108 to actuate the relay 154 and solenoid 102 to set the clutch member 96, and, likewise, when the imprint has been restored to 15 its normal position the opening 115 in the drum 114 will register with an aperture in the web and the relay 171 will operate to energize the solenoid 101 and withdraw the clutch member 96. Preferably the reversing switch 149 is operated 20 simultaneously with the operation of the clutch members 81 and 82 and to this end the reversing switch may be connected with the shaft 88 and, in the present arrangement, it is mounted in a casing 180 and connected with that shaft. 25

At times the imprint on the web may be moved so far from its normal position that the detector will not function. For example, due to some fault in the printing mechanism there might be a wide gap between certain imprints on the web. To enable the speed varying mechanism to be operated to correct such a wide variation I have provided manually operated switches for energizing the relays 154 and 171. As shown in Fig. 12 a switch 181 is connected with the conductor 152 which leads to the coil of the relay 154 and, by a conductor 182 with the conductor 141 and the secondary of the transformer. A second switch 183 is connected with the conductor 169 leading to the relay 171 and with the conductors 182 and 141 leading to the secondary. Thus by manually operating the switches 181 and 183 the solenoids 101 and 102 may be actuated to control the clutches and the speed varying mechanism. 30

The speed varying mechanism may be controlled by detectors of various kinds and in Fig. 11 I have shown a modified form of detector in which the circuit is mechanically closed through the aperture in the web. As there shown, the detector comprises two rotatable parts or contact members 184 and 185 which are slidably mounted in the peripheral wall of a drum 186 which is operated in timed relation to the cutting mechanism. These contact members or plungers are connected through connector rings 187 and conductors 188 and 189 with the conductors 148 and 166, respectively, thus substituting the rotatable parts 184 and 185 for the rotatable members 113 and 114 and their cooperating photo-electric devices. Extending partially about the drum 186 is a segmental contact member 190 which is connected by a conductor 191 with the conductor 141 leading to the secondary of the transformer. The web 21 is carried about guides 192 between the drum 186 and the segmental contact member 190. The drum is so positioned with relation to the cutting mechanism that when the imprint on the web is in its correct position each aperture will lie between the contact members 184 and 185 as the web travels over the segmental contact 190, but if the imprint lags behind its normal position the opening 105 in the web will be brought into line with the contact member 185 and this contact member will be moved by its spring through the opening in the web and into engagement with 55 60 65 70 75

the contact member 190, thus closing the circuit through the relay 154. Inasmuch as contact will be maintained through a considerable period of time the relay will be retained closed for a sufficient period to insure the proper operation of the solenoid 102. When the imprint has been restored to or slightly beyond its normal position the other contact member 184 will operate through the opening 105 in the web to close the circuit through the relay 171 and thus energize the solenoid 101 to interrupt the operation of the speed varying mechanism.

While we have shown and described one embodiment of our invention, together with a modified form of detector, we wish it to be understood that we do not desire to be limited to the details thereof as various modifications may occur to a person skilled in the art.

Having now fully described our invention, what we claim as new and desire to secure by Letters Patent, is:

1. In a machine comprising a device to operate on a web of material at a predetermined location with relation to each of a series of imprints on said web, and means for normally feeding said web of material to said operating device with said imprints in proper relation to said operating device, said web having an aperture arranged in definite relation to each imprint, normally inoperative means for varying the speed at which said web of material is fed to correct a variation in the position of said imprints with relation to said operating device, an electrically operated device to initiate the operation of said speed varying means, a second electrically operated device to interrupt the operation of said speed varying means, a detector comprising two parts actuated in timed relation to said operating device and adapted to operate through apertures in said web to control the circuits for the respective electrically operated devices, and means for reversing the connections between said parts and said electrically operated devices, whereby either part of said detector may be caused to control either of said electrically operated devices.

2. In a machine having a device to operate on a web of material at a predetermined location with relation to each of a series of imprints on said web, means for feeding a web to said operating device, a driving mechanism for said operating device and said feeding means, a device to vary the speed at which said web is fed to said operating device, means including a clutch to operatively connect said speed varying device with said driving mechanism, electro-magnets to move said clutch into and out of its operative position, separate circuits for said magnets, a device controlled by the position of the imprints on said web with relation to said operating device to close the circuit through one of said magnets when said imprints assume an abnormal position, and a similar device to close the circuit through the other magnet after the imprints have been restored to their normal position.

3. In a machine having a device to operate on a web of material at a predetermined location with relation to each of a series of imprints on said web, means for feeding a web to said operating device, a driving mechanism for said operating device and said feeding means, a device to vary the speed at which said web is fed to said operating device, means including a clutch to operatively connect said speed varying device with said driving mechanism, electro-magnets to move said clutch into and out of its operative position,

separate circuits for said magnets, a device controlled by the position of the imprints on said web with relation to said operating device to close the circuit through one of said magnets when said imprints assume an abnormal position, a similar device to close the circuit through the other magnet after the imprints have been restored to their normal position, means for reversing the direction in which said speed varying device is driven by said driving mechanism, and means for reversing the connections between said circuit controlling devices and said magnets.

4. In a machine having a device to operate on a web of material at a predetermined location with relation to each of a series of imprints on said web, means for feeding a web to said operating device, a driving mechanism for said operating device and said feeding means, a device to vary the speed at which said web is fed to said operating device, a shaft, reversible mechanism for causing said shaft to be rotated in either direction by said driving mechanism, means including a clutch to operatively connect said shaft with said speed varying mechanism, electrically operated devices to actuate said clutch, devices controlled by the position of the imprints on said web with relation to said operating device and connected with the respective electrically operated devices to control the operation thereof, and means for reversing the connections between said controlling devices and said electrically operated devices.

5. In a mechanism comprising a device to operate on a web of material at a predetermined location with relation to each of a series of imprints on said web and means for normally feeding said web to said operating device with said imprints in proper relation to said operating device, said web having an aperture arranged in definite relation to each imprint, normally inoperative means for varying the speed at which said web is fed to correct variations in the position of said imprints with relation to said operating device, electrically operated means to control the operation of said speed varying means and having separate circuits to initiate said operation and to interrupt the same, and a detector comprising two parts adapted to separately operate through apertures in said web to close the respective circuits, each circuit having means to maintain the same closed independently of said detector, said parts of said detector being so arranged that one of said parts can operate through an aperture in said web only when the imprint on said web is in the rear of its normal position and the other of said parts can operate through an aperture in said web only when said imprint is in advance of its normal position and the closing of one circuit will initiate the operation of said speed varying means and the closing of the other circuit will interrupt said operation.

6. In a mechanism comprising a device to operate on a web of material at a predetermined location with relation to each of a series of imprints on said web and means for normally feeding said web to said operating device with said imprints in proper relation to said operating device, said web having an aperture arranged in definite relation to each imprint, normally inoperative means for varying the speed at which said web is fed to correct variations in the position of said imprints with relation to said operating device, means including a clutch to control

the operation of said speed varying means, electrical devices operating respectively to set and release said clutch, separate circuits for said electrical devices, and a detector having means operating through an aperture in said web to close the circuit through one of said electrical devices to set said clutch when the imprint on said web has assumed a predetermined position with relation to said operating device and also having means operating through an aperture in said web to close the circuit through the other electrical device to release said clutch when the imprint on said web has assumed another predetermined position with relation to said operating device.

5 7. In a mechanism comprising a device to operate on a web of material at a predetermined location with relation to each of a series of imprints on said web and means for normally feeding said web to said operating device with said imprints in proper relation to said operating device, said web having an aperture arranged in definite relation to each imprint, normally inoperative means for varying the speed at which said web is fed to correct variations in the position of 10 said imprints with relation to said operating device, means including a clutch to control the operation of said speed varying means, electrical devices operating respectively to set and release said clutch, separate circuits for said electrical devices, a relay in each circuit having means for maintaining its circuit closed for an interval after said relay has operated to close the same, an actuating circuit for each relay, and a detector having means operating through an aperture in 15 said web to close one of said actuating circuits when the imprint on said web assumes a predetermined position with relation to said operating device and also having means operating through an aperture in said web to close the other actuating circuit when the imprint assumes another predetermined position with relation to said operating device.

20 8. In a mechanism comprising a device to operate on a web of material at a predetermined location with relation to each of a series of imprints on said web and means for normally feeding said web to said operating device with said imprints in proper relation to said operating device, said web having an aperture arranged in definite relation to each imprint, normally inoperative means for varying the speed at which 25 said web is fed to correct variations in the position of said imprints with relation to said operating device, means including a clutch to control the operation of said speed varying means, electrical devices operating respectively to set and release said clutch, separate circuits for said electrical devices, a detector having means operating through an aperture in said web to close the circuit through one of said electrical devices to set said clutch when the imprint on said web has assumed a predetermined position with relation to said operating device and also having means operating through an aperture in said web to close the circuit through the other electrical device to release said clutch when the imprint on said web has assumed another predetermined position with relation to said operating device, and means controlled by said clutch to open the respective circuits after said clutch has been operated.

30 9. In a web feed control mechanism, means for determining variation in the rate at which the web is fed, electrical means operable by said means when an error in one direction is detected,

means for altering the rate at which the web is fed, and means for maintaining said electrical means in operated condition until an error in the other direction is detected.

10. In a mechanism comprising a device for operating on a web of material, means for continuously advancing said web to said operating device and electrically operated means for varying the speed at which said web is advanced to control the position of an imprint on said web with relation to said operating device, a housing having a wall in supporting engagement with said web and provided with an opening, a light controlled device arranged within said housing to receive light from said opening and having means to control a circuit for said electrically operated means, a source of light arranged to project light toward that side of said web opposite said housing, and a device operated in timed relation to said operating device to cause light from said source to be projected toward said web at predetermined intervals, said web having means located in a definite position with relation to each imprint thereon to control the passage of light from said source through said opening in said housing.

11. In a web feeding mechanism having electrically operated means for controlling the position of an imprint on said web with relation to a device which operates on said web, a detecting device comprising a housing having a wall in supporting engagement with said web and provided with an opening, a light controlled device arranged within said housing to receive light from said opening and having means to control a circuit for said electrically operated means, a hollow element mounted on that side of said web opposite said housing for rotation in timed relation to said operating device and having an opening adapted to register with the opening in said housing, and means mounted within said hollow element for projecting a ray of light through said openings, said web having means arranged in definite relation to each imprint thereon to control the passage of light through the opening in said housing.

12. In a web feeding mechanism having electrically operated means for controlling the position of an imprint on said web with relation to a device which operates on said web, a detecting device comprising a housing having a wall in supporting engagement with said web and provided with an opening, a light controlled device arranged within said housing to receive light from said opening and having means to control a circuit for said electrically operated means, a hollow element mounted on that side of said web opposite said housing for rotation in timed relation to said operating device and having an opening adapted to register with the opening in said housing, and means mounted within said hollow element for projecting a ray of light through said openings, said web having an aperture arranged in a definite position with relation to each imprint and adapted to register with the openings in said housing and said rotatable element when the imprint on said web assumes an inaccurate position with relation to said operating device.

13. In a web feeding mechanism having electrically operated means for controlling the position of an imprint on said web with relation to a device which operates on said web, a detecting device including a housing comprising two compartments and having a wall in supporting en-

gagement with said web, said wall having spaced openings communicating with the respective compartments, light controlled devices arranged in said compartments to receive light from the respective openings and having means for controlling circuits for said electrically operated means, hollow elements mounted on that side of said web opposite said housing for rotation in timed relation to said operating device and having openings adapted to register with the respective openings in said housing, and means within each rotatable element to project a ray of light through the opening therein, said web having means arranged in definite relation to each imprint thereon to control the passage of light from the openings in said rotatable elements through the openings in said housing.

14. In a web feeding mechanism having electrically operated means for controlling the position of an imprint on said web with relation to a device which operates on said web, a detecting device including a housing comprising two compartments and having a wall in supporting engagement with said web, said wall having spaced openings communicating with the respective compartments, light controlled devices arranged

in said compartments to receive light from the respective openings and having means for controlling circuits for said electrically operated means, hollow elements mounted on that side of said web opposite said housing for rotation in timed relation to said operating device and having openings adapted to register with the respective openings in said housing, and means within each rotatable element to project a ray of light through the opening therein, the openings in said elements being so arranged with relation one to the other and to said operating device that when an imprint on said web assumes a position in the rear of its normal position the adjacent aperture will register simultaneously with the opening in one of said rotatable elements and the corresponding opening in said housing and when an imprint on said web assumes a position in advance of its normal position the adjacent aperture will register simultaneously with the opening in the other rotatable element and the other opening in said housing.
